SPOOLING MACHINE

Earl G. Crooks, Elmira, N. Y., assignor to
Chemung Engineering Corporation, Elmira,
N. Y., a corporation of New York

Application June 21, 1934, Serial No. 731,599

8 Claims. (Cl. 242—18)

This invention relates to spooling machines such as are employed in the textile industry for winding thread or yarn on spools, and more particularly to the means for retaining the spools on which the thread is wound or to be wound in proper relation to the spool driving rolls by which the spools are rotated so as to insure a uniform and even drive of the latter.

In U. S. Letters Patent 1,964,785, to be issued to me on July 3, 1934, I disclosed and claimed mechanism for retaining the spools in operative association with their driving rolls which is extremely efficient and satisfactory in operation when the perimeters of the flanges of the spools utilized therewith are concentric with the bodies of the spools. However, experience under various operating conditions has shown that where the perimeters of the spool flanges and the bodies are in a more or less non-concentric relation, as is often the case with spools in which the flanges are not made integral with the bodies or in which the material of which the bodies and flanges are integrally constructed is susceptible of rapid wear or is easily damaged by rough usage, it sometimes happens that the spool will not drive evenly and uniformly because of the tendency of its flanges to follow the guide rolls under the pull of the thread and thus vary the frictional engagement of the thread on the spool body with the driving roll.

The present invention has therefore been developed with a view, among other things, to overcoming this difficulty by the provision of spool retaining means, operating on the same principles as those disclosed and claimed in my said patent but so arranged that it is a matter of no consequence under any conditions of operation if the flanges and bodies of the spools are, within reasonable limits, in non-concentric relation. Consequently, the spool retaining means forming the subject of this application are especially desirable for installation in mills in which a considerable number of such non-concentric spools are in use, for as the latter gradually wear out and are replaced with accurate spools, no changes are required in the spooling machines since the latter, when equipped with the present improvements, will operate equally well with accurate and non-accurate spools.

The principal object of the invention may therefore be considered as the provision of improved means for insuring constant and uniform driving engagement between the body of thread on each spool, or of the spool body itself in the absence of said thread, and the spool driving roll irre-

spective of lack of concentricity between the peripheries of the spool flanges and its body or irregularities or unevenness in the flanges themselves, while, in addition, the said means are so arranged as to facilitate the throwing of the spool into and out of engagement with the driving roll and the holding of an empty or partially filled spool out of engagement with the latter either prior to the initiation of the winding operation or during said operation in case, because of thread breakage or for some other reason, it be desired to temporarily prevent the thread on the spool from being damaged by contact with the rotating driving roll while no thread is being wound upon the spool.

This result is attained, as well as certain other results and advantages hereinafter more particularly pointed out, by providing a pair of guide rolls for cooperation with each of the spool flanges and supporting them from the adjacent finger in such manner that they exert an equalized pressure on the spool flange at spaced points and are free to follow its periphery at all times whereby inequalities or unevenness in the flange or lack of concentricity between its periphery and that of the spool body are automatically compensated without varying the frictional engagement of the body of thread on the spool with the face of the drive roll.

Other objects, purposes and advantages of the invention will hereinafter more fully appear or will be understood from the following description of a preferred embodiment thereof as illustrated in the accompanying drawings in operative combination and association with a spooling machine of the type to which I have referred and of which only so much is shown as is requisite for adequate comprehension of the invention.

In the said drawings, in which like characters of reference designate the same parts in the several figures:

Fig. 1 is a fragmentary front elevation of a portion of a spooling machine provided with the present improvements, a spool having one layer of thread partially wound thereon being shown in operative position in the machine;

Fig. 2 is a fragmentary top plan view of the parts shown in Fig. 1;

Fig. 3 is a fragmentary end elevation thereof partly in section;

Fig. 4 is a fragmentary end elevation corresponding to Fig. 3 but showing the spool after a plurality of layers of thread have been wound thereon, the change in the relation of several parts resulting from the additional quantity of

thread being clearly apparent from a comparison of these two figures;

Fig. 5 is a fragmentary end elevation corresponding to Figs. 3 and 4 but showing the manner in which a spool may be supported on the fingers in non-operative position, and

Fig. 6 is an enlarged fragmentary detail view, partially in section, of two of the guide rolls and adjacent parts shown in the preceding figures.

Referring now more particularly to the drawings, the spooling machine fragmentarily shown therein comprises horizontally extending rails 1, 1 supported at their extremities and in turn supporting the spool retaining fingers and the spool driving mechanism, the traverse mechanism by which the thread is laid evenly on the spool being preferably supported from the fingers. Customarily a series of spools are disposed in spaced axial alignment on each side of the rails 1, 1, and separate driving and traverse mechanisms are provided for each series, but for convenience of illustration I have shown in the drawings and shall herein refer to but one spool S and such portions of the driving and traverse mechanisms as are required for its individual operation.

In accordance with usual practice, the driving mechanism includes a shaft 3 disposed parallel to, below and somewhat in advance of the rails when viewed from the front of the machine as shown in Fig. 1. This shaft is journaled in brackets 4 secured to the rails at intervals by clips generally designated as 5 while collars 6 are secured to the shaft by set screws 6' to restrain it from longitudinal movement during its rotation when the machine is in operation, means (not shown) being provided for effecting rotation of the shaft at a suitable speed. Mounted at intervals on the shaft are driving rolls 7 preferably, and in accordance with the usual practice, provided with a facing 8 of cork or other suitable friction material, the width and diameter of the rolls being such that the faced circumferences thereof will properly drive a generally superjacent spool S through engagement with its body between its end flanges f or with the thread wound thereon, when the spool is in winding position in the machine.

The traversing mechanism, to which reference has been made, guides the thread T onto the spool in a series of adjacent convolutions and consists essentially of a traverse bar 10 extending in front of the upper part of the driving rolls longitudinally of the machine, and having notched guides 11, through which the thread is led to the spools from the respective sources of supply, secured to it at suitable intervals in alignment with the several spools. The bar is arranged for reciprocation at suitable speed and frequency by the customary mechanism (not shown) and is supported at intervals along its length on rolls 12 which are preferably carried by certain of the spool retaining fingers 13 which are extended downwardly and forwardly for the purpose as at 13a, though any other manner of supporting the rolls may be utilized if desired.

These several parts are of course commonly found in one form or another in most types of spooling machines so that no further description of them is necessary, particularly as their specific construction and arrangement forms no part of the present invention and is therefore a matter of choice so long as they are adapted for the performance of their respective functions.

When in winding position, each spool S is located between two of the fingers 13 which are respectively disposed along the rails 1, 1 in pairs and are supported therefrom, the fingers of each pair lying adjacent but above and outside the ends of the respective driving rolls. As all the fingers are preferably of substantially similar construction, excepting those provided, if desired, with the extension 13a, for supporting the traverse bar rolls 12, of which any requisite number may be supplied, a description of but one of them will suffice. Thus, each finger may comprise a pair of similar metal members A, B welded together adjacent their outer portions and provided with opposed central offset portions affording an opening for the passage of a bolt 15 extending through a plate 16 overlying the members and threaded into another plate 17 beneath the rails for adjustably securing the finger thereto. However, it will of course be understood that if desired, each finger may be made of a single casting and may be secured in the rails 1, 1 in any other suitable or convenient manner as the specific form and/or construction of the fingers per se is a matter of choice as long as they afford adequate support for the spool retaining parts hereinafter more particularly described.

Adjacent the end of each finger and outwardly from and above the driving roll, a T-shaped yoke, generally designated as 20, is pivoted on a pin 21 so as to swing freely in a vertical plane. This yoke comprises three arms 22, 23, 24 through the first of which the pin 21 is extended, while each of the others is provided near its outer end with a pin 26 on which is rotatably mounted a guide roll 27 or 28 as the case may be. Each of these rolls, as best shown in Fig. 6, preferably comprises a hollow cylindrical body 29 and an integral flange 30 at that end of the roll which lies adjacent the yoke, while the outer face of the roll is provided with a cork or other suitable, somewhat resilient facing 31 which has a generally conical contour adjacent the flange but is otherwise cylindrical. The rolls are preferably mounted on anti-friction bearings so that they will turn very freely, conveniently and as shown by grooving the inner face of the roll body to provide a race for the reception of balls 32 and forming the opposite race by a pair of cooperative grooved washers 33 mounted on the pin 26 which extends through the yoke, a spacing washer 35 being interposed between the grooved washers and face of the yoke so as to properly locate the roll with respect thereto; after assembly of the parts, the ends of the pin are headed over so as to maintain them in proper relation. However, while this affords a convenient way of mounting the roll, any other suitable means may be utilized provided they are effective to permit its free rotation and to hold it in proper relation with the yoke.

Each yoke is thus free to swing about the pivot pin which preferably, as best shown in Fig. 6, serves to support both yokes carried by each finger and, for limiting this swinging movement when the yoke is turned upwardly and forwardly, a stop pin 36 is mounted on the finger in the path of the arm 22 at a point above and outwardly from the pivot pin 21 so that when the yoke is swung up over center, it will engage the stop as shown in Fig. 5 and be thereby supported in overbalanced position as hereinafter more fully explained.

Assuming the parts to be constructed and assembled substantially as described, it will be understood that prior to placing the machine in operation, the fingers are adjusted along the rails so that each pair lies symmetrically with respect to the adjacent drive roll and the distance between each pair is somewhat greater than the length of the spool to be wound if devoid of projecting trunnions or of the combined length of the spool and trunnions if provided therewith. Under these conditions, after the spool S has been placed in winding position in the machine, its body rests on the driving roll and each of its flanges is engaged by the adjacent guide rolls substantially as shown in Fig. 3 so that when the drive roll rotates in the direction of the arrow in said figure, the spool through frictional engagement with the surface of the drive roll will be rotated in the opposite direction during the winding operation. During the latter, a certain amount of force is required to pull the thread over the guide 12 of the traversing mechanism from the source of supply, and the reaction of this force on the spool tends to pull the latter downwardly and forwardly, thus in effect wedging it between the drive roll and the guide rolls 27, 28 and maintaining a constant or substantially constant frictional engagement with the former. Furthermore, the thrust of the spool against the guide rolls is equalized between them and ultimately taken on the pin 21, just as it is ultimately taken on the pivot of the single guide roll utilized in the construction disclosed in my said patent. Thus, the principle of operation is the same in both cases save that where the two guide rolls are employed and mounted on the swinging yoke so that a two-point instead of a single-point contact with each flange results and the rolls can at all times follow the spool flange, irregularities in the latter or lack of concentricity between its periphery and the barrel of the spool are compensated for and cannot result in varying the frictional engagement between the spool barrel or body of thread thereon and the driving roll, and an even and uniform drive is therefore assured under all conditions.

Moreover, as can readily be observed from Figs. 3 and 4, when the thread is drawn onto the spool from the guide of the traversing mechanism, it does not pass close to the guide rolls at any time during the winding operation. Consequently, even when the parts are so adjusted that the guide rolls considerably overlap the inner edge of the spool flanges and the spool is full or nearly full of thread, contact of the latter with either guide roll during normal winding of the spool is impossible as the "draw" of the thread is always between the guide rolls whenever the spool is in winding position.

In placing the spool in such position in the machine, it is generally preferable to have the yokes at the selected station swung outwardly about their pivots over center and therefore resting against the stops 36, that is, in the position indicated in Fig. 5. The spool with one or more turns of thread wound thereon, can then be rested on the guide rolls, or an empty spool may be rested thereon and the thread then secured thereto; the spool and yokes are then swung upwardly and inwardly as a unit, the flanges being meanwhile held against the guide rolls, until the spool barrel seats on the driving roll which may be either at rest or turning in the direction of the arrows. The winding of the spool is thus initiated and may be continued until the spool is

filled when, by a simple reverse movement in association with the yokes, it may be brought to the position of Fig. 5 preparatory to removal from the machine and insertion of a fresh spool.

This ability to quickly throw the spool out of winding position and thereafter support it on the yokes is a matter of considerable advantage from a practical standpoint, since if the thread should break during the winding operation the machine tender can very quickly throw the spool away from the driving roll to the position of Fig. 5 and keep it there until the thread can be tied preparatory to again putting the spool into operation, thus obviating any roughening or other damage to the outer layer of the thread already wound thereon which frequently occurs if the spool is allowed to rotate against the driving roll for any extended period after a break occurs, as is well understood by those conversant with the industry.

Thus, any spool may be very quickly and easily thrown into or out of operation without interfering in any way with the operation of the other spools, yet maintained adjacent the driving roll in a convenient position and ready for return thereto at the will of the machine tender.

As has been indicated, spool retaining fingers embodying the present invention may be incorporated in spooling or winding machines now in general use in the industry without their extensive reorganization or structural modification inasmuch as the fingers may readily be secured to the rails of such machines in substantially the same manner as and in place of the fingers of other types now in use, by merely removing the latter and substituting therefor the former, and adjusting them so that the guide rolls properly engage the flanges of the spools as herein described. The present invention may thus readily be incorporated in a machine now in use without any serious interruption in its operation and at a relatively small expense.

It may here be pointed out that while the fingers disclosed and claimed in my said patent having but a single guide roll arranged for engagement with each spool flange are generally preferable when the spools employed are of substantially perfect concentricity with respect to their bodies such, for example, as glass, porcelain and like integrally molded spools, I consider the fingers of the present invention more suitable for use in association with spools having separate flanges, as when the latter are made of metal and secured to a wooden or other non-integral body, for in such spools eccentricity of the flanges is of more common occurrence. Furthermore, in some machines and under certain operative conditions the fingers of the present invention may be preferred on account of their ability to support a spool in non-operative position, i. e., out of engagement with the driving roll, although it will of course be understood that this statement is not to be taken as in any sense negative or limiting the possibility of providing the fingers of said patent with suitable means for supporting the spools in non-operable position independently of the guiding rolls.

Although I have herein described one form of my invention with considerable particularity, I do not thereby desire or intend to confine or limit myself specifically thereto as the design, construction and arrangement of the various parts are capable of modification and variation in many particulars, while the principles of the invention may be utilized in connection with many

types of spooling machines other than those to which I have chosen to refer, without departing from the spirit and scope thereof as defined in the appended claims.

5 Having thus described my invention, I claim and desire to protect by Letters Patent of the United States:

10 1. A spool retaining finger for a spooling machine comprising a support, a yoke pivotally carried by the support, and means carried by the yoke at spaced points respectively adapted to be engaged by a spool flange.

15 2. A spool retaining finger for a spooling machine comprising a support, a yoke pivotally secured thereto having divergent arms, and guiding means respectively carried by said arms adapted for engagement by the flange of a spool.

20 3. A spool retaining finger for a spooling machine comprising a support, a yoke pivoted to said support, having divergent arms, a pin carried by each of said arms, and a guide roll supported from each pin in rotatable relation to the yoke.

25 4. A spool retaining finger for a spooling machine comprising a support, a yoke having divergent arms, means for pivotally securing the yoke to the support, guiding means respectively carried by said arms adapted for engagement by the flange of a spool, and a stop secured to the support adapted to limit pivotal movement of the yoke in one direction and thereafter support it in overbalanced relation with respect to the pivotal means.

30 35 5. The combination with a spooling machine comprising a spool driving roll, of a spool retain-

ing finger disposed adjacent each end of the roll, and means pivotally carried by each finger comprising a plurality of rotatable guide rolls adapted to respectively engage the flanges of a spool at spaced points when the spool is seated on the driving roll.

5

6. The combination with a spooling machine having a spool driving roll, of a spool retaining finger disposed adjacent each end of the roll, a yoke pivoted to each finger at a point above and in advance of the axis of the driving roll considered in its direction of rotation, and means carried by each yoke adapted for engagement by a spool when it is seated on the roll.

10

7. In a spooling machine, the combination 15 of a horizontal driving roll, a pair of fingers supported adjacent opposite ends of said roll, a flanged spool between the fingers, a member pivotally supported on each finger at a point above the plane of the axis of the driving roll, and guiding means carried by each member operative through engagement with the spool flanges to restrain the spool from endwise movement and to cause it to hug the driving roll while the thread is being progressively wound upon it.

20

8. In a spooling machine of the character described, a driving roll, a pair of fingers disposed adjacent opposite ends of the roll, a flanged spool between the fingers, a yoke pivotally supported on each of the fingers, and means carried by 30 each yoke adapted to engage a flange of the spool at spaced points on its periphery to thereby maintain it in frictional engagement with the driving roll.
